UNITED STATES PATENT OFFICE.

HUGH T. HUGHES, OF YOUNGSTOWN, OHIO.

ANTICREEPING RAILWAY DEVICE.

1,111,696.

Specification of Letters Patent.

Patented Sept. 22, 1914.

Application filed August 30, 1912. Serial No. 717,985. Renewed December 5, 1913. Serial No. 804,943.

To all whom it may concern:

Be it known that I, HUGH T. HUGHES, a citizen of the United States, residing at Youngstown, in the county of Mahoning and State of Ohio, have invented certain new and useful Improvements in Anticreeping Railway Devices; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in devices for preventing railway rails from creeping and comprises a simple and efficient device of this nature having various details of construction and combinations and arrangements of parts which will be hereinafter fully described, shown in the accompanying drawings and then specifically defined in the appended claims.

The invention consists further in the provision of an anti-creeping device for keeping the railway joints in alinement and uniformly spaced, thereby preventing liability to accidents incident to rails not holding proper alinement, the device serving to take the place of the ordinary tie plates and assure the lengthening of the life of the ties by the preventing of the rail base from sinking down into the tie as the train rolls over the railway rails.

My invention is illustrated in the accompanying drawings, in which:—

Figure 1 is a cross sectional view through my device shown as applied to a railway rail. Fig. 2 is an elevation of the invention, and Fig. 3 is a top plan view.

Reference now being had to the details of the drawings by letter, A designates a plate provided with spike holes B formed at any suitable locations and through which spikes may be driven to engage the flanges C of a rail D resting upon the plate. Upon one edge of said plate is a flange E which has an arched slot E' formed by a laterally and downwardly projecting portion thereof, as shown clearly in the drawings, and F designates a loosely mounted cam having two convexed toothed edges H which are adapted to bite into the upper surface of the flange

C of the railway rail in the event of the latter having any tendency to move longitudinally in one direction or the other. The upper edge of said cam F is convexed and is adapted to contact with the bottom of the wall of the slot formed in the flange E and in which position the two series of teeth formed upon the cam member will rest against the flange of the rail. Projecting from the bottom of the plate are ribs K which are adapted to bite into the tie and prevent the plate from moving from its place.

In adjusting in place my improved device for preventing the rails from creeping, the cam member F is inserted with its upper end in the slot of the flange E before the plate is moved to the position shown in Fig. 2 of the drawings and, when the parts are adjusted as shown, the cam member will snugly contact at its upper and lower edges with the wall of the slot and the upper surface of the flange of the rail respectively. The plate being securely held from moving, any tendency of the rail to move will cause the cam to rock and tightly check movement of the rail.

What I claim to be new is:—

1. A device for preventing railway rails from creeping comprising a plate upon which the flange of a railway rail is adapted to rest, said plate having an upright portion with an undercut slot formed in the lateral projection thereof, and a cam member adapted to engage said slot and the upper surface of the flange of a railway rail, as set forth.

2. A device for preventing railway rails from creeping comprising a plate upon which the flange of a railway rail is adapted to rest, said plate having an upright portion with an undercut slot formed in the lateral projection thereof, a cam having its upper edge convexed and engaging a similarly shaped wall of the slot and its lower edge serrated and adapted to engage the upper surface of the flange of a rail, as set forth.

3. A device for preventing railway rails from creeping comprising a plate upon which the flange of a railway rail is adapted to rest, said plate having an upright portion with an undercut slot formed in the lateral projection thereof, a cam having its upper edge convexed and engaging a simi-

larly shaped wall of the slot and having its lower edge provided with two convexed portions, each having a series of serrations upon the edge thereof and adapted to engage the upper surface of the flange of a

In testimony whereof I hereunto affix my signature in the presence of two witnesses.

HUGH T. HUGHES.
